UNITED STATES PATENT OFFICE.

RICHARD TITUS, OF BOWLING GREEN, OHIO.

DEVICE FOR PULLING BEETS, THISTLES, AND THE LIKE.

1,205,414.

Specification of Letters Patent.

Patented Nov. 21, 1916.

Application filed March 11, 1916. Serial No. 83,588.

To all whom it may concern:

Be it known that I, RICHARD TITUS, a citizen of the United States, residing at Bowling Green, in the county of Wood and State of Ohio, have invented a new and useful Device for Pulling Beets, Thistles, and the like, of which the following is a specification.

This invention relates to a device for pulling beets, thistles and the like, one of the objects being to provide a device of this type which can be easily carried from place to place and which has jaws adapted to be forced into the ground and to be shifted relative to each other so as to loosen and clamp upon the growth to be removed, simple means being provided for actuating the jaws and additional means being employed whereby the jaws can be forced into the ground by either or both hand and foot pressure.

A further object is to provide an implement of this character which is formed of but few parts, cheap to manufacture, and will not easily get out of order.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

40. In said drawings:—Figure 1 is a front elevation of the implement. Fig. 2 is a side elevation. Fig. 3 is a section on line A—B Fig. 1.

Referring to the figures by characters of reference 1 designates the main holding strip, the same being slidably engaged by yokes 2 having inturned ends 3, these yokes being secured to the end portions of a slideable holding strip 4 extending longitudinally of the strip 1 but much shorter than said strip. The upper end portions of the strips 1 and 4 have outstanding grips 5 and 6 respectively.

Extending through the lower end portion 55 of the main strip 1 is a pin 7 constituting means for pivotally connecting to said strip

crossed levers 8 each of which is provided, at its lower end, with a spoon shaped jaw 9 merging into a tongue 10 constituting a digging element. The jaws are oppositely disposed as shown. One end portion of the pin 7 projects laterally beyond the strip 1 to constitute a foot rest 11.

Pivots connected to the lower end portion of the slideable strip 4 are links 12 which are pivotally and adjustably connected to the upper ends of the respective levers 8. Thus it will be seen that when the strip 4 is drawn upwardly along the strip 1 the links 12 will pull on levers 8 and move the jaws toward each other to bring their tongues 10 into contact at their lower edges. However, when strip 4 is shifted in the opposite direction, the jaws will be swung apart.

75 A longitudinal series of openings 13 is formed within the strip 1 and any one of these openings is adapted to receive a stop pin 14 connected to one of the links 12 by a chain 15 or the like. This pin extends into the path of the upper end portions of links 12 and limits the movement of said links toward the pivot 7.

In using the implement the grip or handle 6 is thrust downwardly away from the handle 5 thus to cause the toggle links 12 to press against levers 8 and swing the jaws 9 apart. The tongues 10 on the jaws are placed against the surface of the ground at opposite sides of the growth to be pulled and if the ground is soft the jaws are thrust into the ground simply by pressing downwardly on the two handles 5 and 6. If the downward movement of the links 12 and strip 4 has been stopped by the inserted pin 14, the jaws can be thrust into the soil simply by pressing downwardly on the handle 6. After the jaws have been pressed to the desired depth the handle 6 is pulled upwardly relative to handle 5 thus to force jaws 9 to move toward each other and clamp between them the growth to be removed. Further upward pulling on the handle will result in the withdrawal of the jaws from the ground, the growth therebetween being lifted therewith.

100 Should the ground be hard and it be difficult, consequently, to force the jaws into the ground by pressure upon one or both of the handles, a foot can be placed on the rest 11 and pressure thus exerted upon the implement.

The device can be used efficiently as a means for removing beets and thistles from the ground, for transplanting vegetables and for various other similar purposes. By utilizing the pin 14 and placing it in a selected opening 13, the relative movement of the jaws 9 can be controlled and it becomes possible simply by pushing downwardly on the handle 6, to force the jaws apart and at the same time press them into the soil.

It will be seen that the entire device is very simple, durable and compact and can be easily and cheaply manufactured. It is comparatively light and thus can be carried from place to place without inconvenience.

What is claimed is:—

1. An implement of the class described including parallel members movable longitudinally relative to each other, a handle upon each member, crossed levers fulcrumed upon one of the members, opposed jaws carried by the respective levers, link connections between the other member and the respective levers.

2. An implement of the class described including parallel members movable longitudinally relative to each other, a handle upon each member, crossed levers fulcrumed upon one of the members, opposed jaws carried by the respective levers, link connections between the other member and the respective levers, and adjustable means for limiting the relative movement of the members.

3. An implement of the class described including parallel members, a slidale connection therebetween, handles upon the re-

spective members, crossed levers fulcrumed upon one of the members, opposed jaws carried by the respective levers, each jaw having a terminal tongue, link connections between said levers and the other member, and a foot rest carried by the lever carrying member.

4. An implement of the class described including a member, crossed levers fulcrumed thereon, opposed jaws carried by the respective levers and having terminal digging tongues, a second member slidale longitudinally upon the first mentioned member, link connections between said second member and the levers, and handles connected to the respective members.

5. An implement of the class described including a member, a pivot pin extending therethrough and forming a foot rest, crossed levers fulcrumed upon said pin, opposed concavo-convex jaws upon the respective levers and having terminal digging tongues, a pin adjustably connected to said member and constituting a stop, a second member slidale longitudinally on the first mentioned member, and link connections between said second member and the respective levers, and handles upon the respective members.

In testimony that I claim the foregoing as my own, I have hereto affixed my signature in the presence of two witnesses.

RICHARD TITUS.
